UNITED STATES PATENT OFFICE.

LOUIS COATALEN, OF WOLVERHAMPTON, ENGLAND, ASSIGNOR OF ONE-HALF TO
SUNBEAM MOTOR CAR COMPANY LIMITED, OF WOLVERHAMPTON, ENGLAND.

V-TYPE INTERNAL-COMBUSTION ENGINE.

1,248,265.

Specification of Letters Patent. Patented Nov. 27, 1917.

Application filed October 24, 1916. Serial No. 127,492.

To all whom it may concern:

Be it known that I, LOUIS COATALEN, a subject of the King of Great Britain, and resident of Wolverhampton, in Staffordshire, England, have invented certain new and useful Improvements in V-Type Internal-Combustion Engines, of which the following is a specification.

This invention relates to internal combustion engines having cam shafts driven by a train of gears from the crank shaft, particularly such as are used on aeroplanes, and its object is to provide improved grouping and operation of the auxiliaries and ignition devices. Among the former may be mentioned the water and oil pumps, the oil filter and the dynamo driving mechanism. These auxiliaries do not require to be accurately timed in relation to the crank shaft, but the ignition devices must be accurately timed. Therefore no great skill is called for in removing and replacing the auxiliaries, but the fitting of an ignition device is an operation which requires great care to insure that it is correctly timed, as will be readily understood. The auxiliaries and ignition devices ought also to be placed where they are easily accessible, and in some cases have to be fairly frequently removed, so that ease of removal is important. It is the object of this invention to comply with these requirements without employing special driving gears and driving shafts.

In the accompanying drawings, Figure 1 is a rear view of an engine having two rows of cylinders mounted upon one crank chamber at an angle to one another, which is constructed in accordance with this invention and is intended chiefly for use on aeroplanes.

Fig. 2 is a side view of part of the same.

Fig. 3 is a face view of the rear cover plate of the crank chamber, and

Fig. 4 is a longitudinal section showing a bracket and spindle for driving a dynamo.

Like letters indicate like parts throughout the drawings.

In this arrangement, the crank chamber cover plate A at the rear end of the engine has bolted to it the water pump B, the oil filter C, and a casing containing two oil pumps D and E. These two pumps are

fitted at opposite ends of a spindle, the axis of which is shown at D², driven from the crank shaft Z by skew gears E² E³ in such a way that when the cover plate A is fitted the skew gears slide into mesh and vice versa as will be readily understood.

The water pump B is provided with either a dog clutch or an equivalent connection so that the driving coupling is automatically broken when the cover plate is removed. For example, the connection between the pump spindle and its driving shaft may be similar to that described later with reference to the connection for the spindle L of a dynamo. If desired the spindle driving the oil pumps may be inclined so that the lower oil pump E lies approximately centrally and draws the oil straight out of the central sump F beneath the crank chamber C.

The cover plate A may also have bolted to the bosses J by bolts J² a bracket K for a short spindle L carrying the chain sprocket M for driving a dynamo and a clutch for connecting this with the shaft. The clutch in the case illustrated consists of a fixed plate M² and a movable plate M³ acted upon by a spring M⁴ so that the sprocket M is gripped between the fixed and movable plates, but can be released by moving the plate M³ to the left. It will be seen that the bracket K is bolted to the cover plate A by three bolts or the like located at J², and that the spindle L is driven by one of the engine shafts, preferably the crank shaft Z. The connection between the spindle and shaft is of such a nature that it can slide into and out of mesh. Thus the end of the shaft Z may have a diametrical slot Z² and a diametrical tongue L² may engage this. It will be clear that when the bolts J² are disconnected the bracket K can be removed. Also that the cover plate A with the bracket K in place can be detached and replaced without any difficulty being experienced with reference to the couplings between the operating shafts on the engine and the spindles of the auxiliaries such as the spindle L of the dynamo drive, and the spindle of the water pump.

The latter is preferably driven by one of the intermediate train of gears between the

crank shaft Z and the cam shafts, which are located at the top of the cylinders O. The axis of the intermediate gear which drives the water pump is at B².

- 5 The water pump, oil pumps, and dynamo drive do not require to be accurately timed relative to the crank shaft, but as the magnetos or other ignition devices must be accurately replaced after removal it is there-
10 fore desirable that these should not be carried by the lower cover plate A. Consequently they are carried by the upper timing gear cover plates P which inclose the greater part of the train of gearing between
15 the cam shafts and the crank shaft. The magnetos are therefore arranged at the accessible end of the engine as shown and can conveniently be controlled by a single rod which may be interconnected with the
20 throttle valves of the carbureter. Thus there may be a single shaft R coupled by links R² with the contact breakers of both magnetos S S² so that the two magnetos can be controlled simultaneously.
25 The crank chamber cover plate A when re-
moved takes with it the oil pumps D E, water pump B, oil filter C, and dynamo driving mechanism, and when the mechanism is being taken to pieces it is not necessary to dis-
30 mantle each of these separately. Further, all the external connections, such as the water and oil pipes are arranged at the accessible end of the engine, and close together, and they can all be within easy view of the
35 aviator when the engine is fitted to an aeroplane. In addition, all the auxiliaries, ignition devices, and the spindle for the oil pump are driven directly by shafts or gears which are essential to the engine and are
40 not specially provided for the driving of the auxiliaries. This results in simplicity and reduction of weight, as will be readily understood.

Obviously each timing gear cover P may

carry two or more magnetos instead of one 45 each as illustrated.

What I claim as my invention, and desire to secure by Letters Patent, is:—

1. In an internal combustion engine, the combination of a crank chamber, cylinders 50 thereon, a crank shaft, a cam shaft supported above said cylinders, a gear train between said crank shaft and said cam shaft, a lower cover plate over part of said gear train, removable without disturbing said 55 train, auxiliaries carried by and removable with said cover plate, an upper cover plate over the upper part of said train, an ignition device upon said second cover plate, easily disengageable driving connections between said auxiliaries and said gear train, and driving connections between said ignition device and said gear train, substantially as set forth.

2. In an internal combustion engine, the 65 combination of a crank chamber, two rows of cylinders thereon, a crank shaft, cam shafts supported above said cylinders, trains of gearing between said crank shaft and said cam shafts, a lower cover plate attached 70 to said crank chamber and inclosing part of said trains of gearing which is removable without disturbing said trains, auxiliaries carried by and removable with said cover plate, an upper cover plate to each of said 75 trains, an ignition device carried by each of said upper cover plates and driven by said trains, and easily disengageable connections between said auxiliaries and part of said train of gearing, substantially as set 80 forth.

In testimony whereof I have signed my name to this specification in the presence of two subscribing witnesses.

LOUIS COATALEN.
